UNITED STATES PATENT OFFICE.

JEREMIAH MEARS WATSON, OF SHARON, MASSACHUSETTS.

SHANK-STIFFENER FOR BOOTS OR SHOES.

SPECIFICATION forming part of Letters Patent No. 372,728, dated November 8, 1887.

Application filed November 30, 1885. Serial No. 184,281. (No model.)

To all whom it may concern:

Be it known that I, JEREMIAH MEARS WATSON, of Sharon, in the county of Norfolk, of the Commonwealth of Massachusetts, have invented a new and useful Improvement in the Manufacture of Shoe-Shank Stiffeners; and I do hereby declare the same to be described in the following specification, and represented in the accompanying drawings, of which—

10 Figure 1 is a transverse section, and Fig. 2 a bottom view, of a shoe-shank stiffener of my improved kind. Fig. 3 is a transverse section of its two parts, as sewed together and arranged for being so connected.

15 My invention enables me to utilize much of what is generally condemned as waste pieces of sole-leather, such as, though long enough, are not of sufficient width for being converted into an entire shank—that is, one without a seam 20 extending from end to end of it.

In carrying out my invention, the nature of which is defined in the claims hereinafter presented, I take two pieces, A and B, of leather, each of which is of a suitable width and length, 25 and has one longitudinal edge of it straight; and I scarf or bevel the piece at such edge in manner as shown at *a* in Fig. 3, so that the plane of the beveled edge shall be at an acute angle with the outer surface of the piece when

30 the two pieces are arranged together, face to face, in manner as shown in Fig. 3. Having thus beveled the two pieces and arranged them flatwise against one another, as shown in said Fig. 3, I connect them by stitching or 35 sewing *b*, going through both transversely, somewhat loosely, and at the vertex of the angle which their beveled edges make with each other. Having done this, I turn both strips outwardly from each other until their beveled 40 edges meet in close contact, as shown in Fig. 1, in which case the two strips or pieces A and B will stand at an obtuse angle to each other, transversely of them.

If desirable, the pieces can be glued or other-

wise connected together at their edges in contact; but, generally speaking, the stitching will suffice, it serving by its arrangement not only to secure them to each other, but to operate like a hinge to admit of their being turned or moved outwardly into an inclination with 50 each other, as represented in Fig. 1.

The shoe-shank stiffener so made may be re-enforced, when desirable, by one or more pieces of material properly applied to it. By constructing it of two pieces beveled on their 55 inner edges and laid face to face, so that their beveled edges shall stand at a re-entering angle, and connecting said pieces by stitches going through both transversely at the vertex of the angle, such pieces can afterward be 60 readily turned into positions, as shown in Fig. 1, in which the beveled edges are represented as in close contact throughout both of them.

By making the stiffener in two pieces instead of one, there are benefits to be obtained. The 65 requisite arch is given in a simple way, as the pieces are united without crimping or shaping the leather. Also, by this greater elasticity is imparted to the stiffener, so that while the stiffener stiffens the shoe at the same time it 70 has an elastic, yielding, relieving rigidity in the shoe-shank.

I claim—

1. As an improved manufacture, a shoe-shank stiffener, substantially as described, 75 composed of two separate pieces of leather or material beveled on their longitudinal connected edges and stitched to each other, as set forth.

2. As an improved manufacture, a shoe-shank stiffener composed of two separate pieces of leather or material inclined to each other transversely, and longitudinally connected, as set forth.

JEREMIAH MEARS WATSON.
